UNITED STATES PATENT OFFICE.

GEORGE G. GREENE, OF PAINESVILLE, OHIO.

TRACK-FASTENER.

1,263,552.

Specification of Letters Patent. Patented Apr. 23, 1918.

Application filed February 21, 1918. Serial No. 218,570.

To all whom it may concern:

Be it known that I, GEORGE G. GREENE, a citizen of the United States, residing at Painesville, in the county of Lake and State 5 of Ohio, have invented certain new and useful Improvements in Track-Fasteners, of which the following is a specification, reference being had to the accompanying drawings.

10 This invention relates to certain improvements in track fasteners and has relation more particularly to a device of this general character especially designed and adapted for use in connection with metallic ties, 15 and it is an object of the invention to provide a track fastener of this general character having novel and improved means whereby it may be applied readily and effectively together with means for maintaining the same in operative position.

It is also an object of the invention to provide a novel and improved device of this general character which also serves to effectively brace a rail against turning over, and 25 prevent track spreading.

Another object of the invention is to provide a novel and improved device of this general character which may be readily applied or removed and which can be employed with advantage in connection with shims insertible between a tie and a rail for raising or lowering the rail as may be occasioned during the different seasons of the 30 year.

35 The invention consists in the details of construction and in the combination and arrangement of the several parts of my improved track fastener whereby certain important advantages are attained and the device rendered simpler, less expensive and otherwise more convenient and advantageous for use, as will be hereinafter more fully set forth.

The novel features of my invention will 45 hereinafter be definitely claimed.

In order that my invention may be the better understood I will now proceed to describe the same with reference to the accompanying drawings, wherein:

50 Figure 1 is a view partly in side elevation and partly in section illustrating track fasteners constructed in accordance with an embodiment of my invention, and in applied position;

Fig. 2 is a fragmentary view partly in end 55 elevation and partly in section illustrating my improved fasteners as herein embodied and in applied position;

Fig. 3 is a view in top plan of the structure illustrated in Figs. 1 and 2 with certain 60 of the parts of the fasteners indicated by dotted lines;

Fig. 4 is a fragmentary view in top plan of a tie and shim positioned thereon; and

Fig. 5 is a view in perspective of one of 65 my improved track fasteners as herein disclosed.

As disclosed in the accompanying drawings T denotes a metallic tie of the well known Carnegie type and upon which is 70 rested a standard rail R. Coacting with the opposite flanges of the rail are my improved fasteners F and F'. The fastener F coacts with the outer side of the rail and is of such construction as to effectively brace the rail 75 in a manner to prevent turning over.

The fasteners F and F' include the heads H and H' respectively. The head H snugly fits between the outer flange and the ball of the rail and is of such length as to afford 80 a substantial brace to the rail. Depending from the end face of each of the heads H and H' is a shank 1 substantially circular in cross section and which has provided at its outer or free end a lateral extension 2 ex- 85 tending longitudinally of the coacting head H' and H and in a direction toward the inner end thereof. The bottom face of the extension 2 and the outer face of the shank 1 are rounded and in continuity in order to 90 facilitate the insertion of the shank 1 through the opening 4 suitably positioned in the upper portion of the tie T.

In applying the fastener F or F' the shank is initially inserted with the coacting 95 head H or H' thereof having its longitudinal axis disposed substantially in parallelism with the rail R. The head H or H' is then rotated to properly engage the rail. The desired rotation can readily be obtained 100 by a few blows imposed upon the outer end portion of the head H or H' by a small hammer or other implement. A side of each of the shanks 1 and its coacting head H or H' is provided with a slot or channel 5 extending 105 longitudinally of the shank 1 and open at opposite ends. When the coacting head H or H' is operatively engaged with the adjacent

flange of the rail R, said slot is in register with a groove or channel 6 formed in the wall of the coacting opening 4. The locking key 7 is then seated within the registering slots or recesses 5 and 6 and said key is preferably of a length in excess of the groove or slot 5 so that by bending the end the key 7 is prevented from working upwardly under the influence of the vibrations occasioned 10 by the passing rolling stock over the rail.

To further assure the seating of the key 7 I find it of advantage to provide the upper end thereof with the head 8. This head 8 affords an additional weight which serves to 15 cause the key to drop when loosened by vibration. This head 8 preferably extends outwardly and laterally of the upper end of the key to afford a lip or extension with which a suitable implement may be engaged 20 when it is desired to entirely withdraw the key.

In track beds it often occurs that a rail will be caused to rise upon the swelling of the bed at spots incident to the freezing in 25 winter and to lower after a thaw. My improved fasteners may be employed with convenience and facility to effect the requisite rising and lowering of the rail. With my improved fastener a rail may be readily elevated after a thaw by inserting between the base of the rail and the top of the tie T a shim S preferably of wood and which is provided adjacent its opposite ends with suitably positioned openings 9 adapted to register with the openings 4 in the tie T proper and the wall of each of said openings 9 is provided with a slot or groove 10 adapted to register with the groove or slot 6 in the wall of the coacting opening 4 so that the key 7 may 30 be properly inserted to lock the fastener in position relative to the rail. When the track bed is caused to rise by freezing or from other cause the fasteners F and F' may be readily removed to permit the withdrawal of the shim and which withdrawal results in the lowering of the rail. After the shim has been removed a new set of fasteners F and F' are applied which are constructed in 35 substantially the same manner as herein disclosed and illustrated with the exception that the shanks 1 thereof must be of a length less than the length of the first set equal to the thickness of the shim.

From the foregoing description, it is 55 thought to be obvious that a track fastener constructed in accordance with my invention is particularly well adapted for use by reason of the convenience and facility with which it may be assembled and operated and 60 it will also be obvious that my invention is susceptible of some change and modification without departing from the principles and spirit thereof and for this reason I do not wish to be understood as limiting myself to 65 the precise arrangement and formation of

the several parts herein shown in carrying out my invention in practice except as hereinafter claimed.

I claim:

1. In combination with a tie provided 70 with an opening and a rail resting thereon, a fastener including a head, an end portion of said head being adapted to overlie a flange of the rail, a shank depending from the lower face of the head at substantially 75 the longitudinal center thereof, the lower or free end of said shank being provided with a lateral extension extending inwardly of the head and longitudinally thereof, the side faces of the head and shank being provided 80 with a groove extending longitudinally of the shank, a wall of the opening being provided with a groove adapted to register with the groove of the fastener when the head of said fastener is operatively engaged 85 with the flange of the rail, and a key insertible within said registering grooves.

2. In combination with a tie provided 90 with an opening and a rail resting thereon, a fastener including a head, an end portion of said head being adapted to overlie a flange of the rail, a shank depending from the lower face of the head at substantially 95 the longitudinal center thereof, the lower or free end of said shank being provided with a lateral extension extending inwardly of the head and longitudinally thereof, the side faces of the head and shank being provided with a groove extending longitudinally 100 of the shank, a wall of the opening being provided with a groove adapted to register with the groove of the fastener when the head of said fastener is operatively engaged with the flange of the rail, and a key insertible within 105 said registering grooves, the upper end portion of the key being weighted.

3. In combination with a tie provided 110 with an opening and a rail resting thereon, a fastener including a head, an end portion of said head being adapted to overlie a flange of the rail, a shank depending from the lower face of the head at substantially 115 the longitudinal center thereof, the lower or free end of said shank being provided with a lateral extension extending inwardly of the head and longitudinally thereof, the side faces of the head and shank being provided with a groove extending longitudinally of the shank, a wall of the opening being provided 120 with a groove adapted to register with the groove of the fastener when the head of said fastener is operatively engaged with the flange of the rail, and a key insertible within 125 said registering grooves, the inner end portion of the head snugly fitting between the base flange and ball of the rail.

4. In combination with a tie provided 130 with an opening and a rail resting thereon, a fastener including a head, an end portion

of said head being adapted to overlie a flange of the rail, a shank depending from the lower face of the head at substantially the longitudinal center thereof, the lower or 5 free end of said shank being provided with a lateral extension extending inwardly of the head and longitudinally thereof, the side faces of the head and shank being provided with a groove extending longitudinally of the shank, a wall of the opening being provided with a groove adapted to register with the groove of the fastener when the head of 10 said fastener is operatively engaged with the flange of the rail, a key insertible within said registering grooves, and a shim insertible between the rail and tie and provided with an opening registering with the opening in the tie.

5. In combination with a tie provided 20 with an opening and a rail resting thereon, a fastener including a head, an end portion of said head being adapted to overlie a flange of the rail, a shank depending from the lower face of the head at substantially

the longitudinal center thereof, the lower or 25 free end of said shank being provided with a lateral extension extending inwardly of the head and longitudinally thereof, the side faces of the head and shank being provided with a groove extending longitudinally of 30 the shank, a wall of the opening being provided with a groove adapted to register with the groove of the fastener when the head of said fastener is operatively engaged with the flange of the rail, a key insertible within 35 said registering grooves, and a shim insertible between the rail and tie and provided with an opening registering with the opening in the tie, the walls of the openings of the shim being provided with grooves 40 adapted to register with the grooves in the wall of the opening of the tie.

In testimony I hereunto affix my signature in the presence of two witnesses.

GEORGE G. GREENE.
